UNITED STATES PATENT OFFICE.

AUSTIN C. WHIDDEN, OF LANCASTER, CALIFORNIA.

VALVE-OPERATING MEANS.

Application filed October 11, 1926. Serial No. 140,778.

This invention relates to improvements over the invention described and claimed in my copending application executed October 25, 1926, filed November 3, 1926, Serial No.

5 145,922.

This invention relates to fluid control devices, and more particularly to means for opening and closing the valves of double faucets used in bath tubs, showers and the 10 like for controlling a stream of hot and cold water and mixing the same in varying proportions and varying degrees of temperature and delivering the same when so mixed.

15 The general object of my invention is to provide an improved single control means for operating the valves of standard double compression valve faucets.

A more particular object is to provide 20 novel means for operating the valves of double faucets by a single control, and which means will effectively hold the valves closed or opened to any desired degree until such means are operated in the proper manner 25 by the user.

A further object is to provide a novel attachment for operating the valves of, and which may be easily and quickly applied to, a standard double faucet having compres- 30 sion valves.

In carrying out my invention I provide a simple, unitary attachment that may be easily and quickly attached to standard compression valve double faucets by simply re- 35 moving the standard handles therefor and unscrewing the packing gland nut, applying my attachment and reseating said nut, after which both valves may be controlled by a single handle.

40 Features of the invention are shown in the construction, combination and arrangement of the parts.

Other objects, advantages, and features of 45 invention may appear from the accompanying drawing, the subjoined detail description and the appended claims.

The accompanying drawing illustrates the invention in a form I at present deem preferable.

50 Figure 1 is a view partly in plan and partly in horizontal section, taken on line 1—1, Fig. 2, showing my invention as applied to a standard double faucet.

Fig. 2 is a longitudinal vertical sectional view partly in elevation, and taken on line 55 x^2 , Fig. 1.

Fig. 3 is a transverse vertical sectional view taken on line x^3 , Fig. 1.

Fig. 4 is a transverse vertical section taken on line x^4 , Fig. 2.

Fig. 5 is a horizontal section taken on irregular line 5—5, Fig. 2.

Fig. 6 is a detail elevational view of one of the valve operating pinions.

My valve operating mechanism A is shown 65 applied to a standard double faucet B having compression valves.

The faucet B is preferably of standard construction that may be purchased on the open market and I do not make any claim 70 in this application to such construction which comprises the usual casting b, formed with inlets 1 and 2, outlet 3, mixing chamber 4 interposed between said inlets and outlet, and valve housings 5 and 5' extending 75 from casting b and in which are housed screw or compression valves 6 and 7, respectively, for controlling the passage of cold and hot water from the inlets 1 and 2 into said mixing chamber 4. The valves 6 and 7 are each formed with a thread 8 which engages a thread 9 in the valve housing and by rotation of the valves 6, 7 such threads lower the valves onto their seats 10 or raise the valves off their seats depending 80 on the direction the valves are turned.

My invention includes an attachment that may be easily secured to casting b without drilling holes therein, and comprises pinions 85 11 and 12 that are fitted on the outer squared ends 13 and 14 of the stems 15 and 16 of valves 6 and 7, respectively. Racks 17 and 18 mesh with said pinions, respectively, and are mounted for sliding movement in U-shaped rack guides 19 and 20 that are fulcrumed at their lower portions 90 on the valve stems 15 and 16 and are fulcrumed on their upper ends on the pinions 11, 12.

A crank wheel 21 to which said racks 17, 18 are pivotally connected is provided with a shaft 22 to the outer end of 95 which a handle 23 is secured. A cover 24 through which shaft 22 extends encloses said pinions, racks, guides, and crank wheel, and said cover is secured to and supported by 100 a supporting or base member 25 that it se- 105

- surely mounted on the faucet B as will be more fully hereinafter set forth.
- The pinions 11 and 12 are formed with toothed portions 26' and with cap-shaped hubs 26 extending therefrom, and said pinions are provided with square sockets 27 to receive the square ends 13, 14 of valve stems 15, 16, and said pinions are secured on said valve stems by screws 28 that extend through and engage the tops of said hubs and are screwed into the outer ends of said valve stems. The rack guides 19 and 20 are U-shaped, being formed with lower members 29, upper members 30 and intermediate connecting members 31. The valve stems 15, 16 extend through the lower members 29 of the rack guides 19, 20 and the pinion hubs 26 extend through the upper members 30 of said guides. The racks 17, 18 engage the inner sides of the intermediate members 31 of said guides and are thereby respectively maintained in mesh with the pinions 11, 12. The intermediate connecting members 31 of guides 19, 20 are formed with recesses 32 in which the racks 17, 18 slide, and such racks are thereby prevented from moving upwardly with the pinions 11, 12 when said pinions are rotated to raise the valves 6 and 7 off their seats.
- The crank wheel 21 consists of a pair of spaced disks 33 and 34 secured on the shaft 22 and the racks 17, 18 are pivotally connected by pins 35, 36 to said crank wheel between said disks, preferably at points about 90 degrees apart and in such position that, upon a half revolution of the wheel 21 in clockwise direction from the position shown in Fig. 1, the cold water valve 6, through the medium of the rack 17 and pinion 11, will be rotated so as to be fully opened and closed, while the hot water valve 7 will be fully opened, as will be apparent from Fig. 1. The rack 18 is bowed at 37 so as not to contact with the shaft 22 when the rack 18 is moved to open valve 7.
- The base member 25 comprises an elongate bar 40, a centrally disposed stud 41 standing from said bar intermediate its ends, and which is connected to a plate 42 formed on the upper end of said stud and to which cover 24 is secured to form a housing. The bar 40 is formed at its ends with enlargements 43 provided with openings 45, through which openings are extended the valve housings 5 and 5', of the faucet B after the packing nuts 46 are removed. The bar 40 when connected to double faucets of the type shown preferably rests upon the upper wall of the mixing chamber 4. Bolts 47 extend through the ends of the plate 42 and the bar 40 and nuts 48 screwed onto the lower ends of said bolts engage the under side of said bar 40. Spacing sleeves 49 surrounding said bolts between bar 40 and plate 42 properly space the bar and plate apart. The plate 42 is provided with openings 50, 51 through which extend the valve stems 15, 16, respectively. The cover 24 is formed with vertical embossments 52 in opposite corners thereof which rest upon plate 42 and support the cover 24 on the plate with the lower edges of the cover 24 overhanging the edges of the plate. The cover 24 is secured to plate 42 by screws 53 extending through the embossments 52. The shaft 22 is journalled in a bearing 54 formed in the stud 41 and in a bearing 55 formed in a boss extending from the upper wall of cover 24. The packing nuts 46 engage bar 40 and securely hold the attachment in position on the valve casting b.
- The guides 19, 20 are fitted in working contact between plate 42 and the upper wall of cover 24 and the valve stems 15, 16 extend loosely through the lower members 29 of said guides and the hubs 26 extend loosely through the upper members 30 of said guides and through cover 24 so that the valves 6, 7 and their pinions 11, 12 may be raised or lowered to open or close the valves.
- Although I have shown my attachment as applied to a double faucet which has a common outlet, it is apparent that my device may be attached to a series of two single faucets, which for the purpose of this application may be considered a double faucet.
- In Fig. 2 I have illustrated the valves as being provided with right and left hand threads. However, it is believed apparent that, if my device is desired to be attached to valves having right hand threads, this may be easily accomplished by simply positioning the rack 17 so as to engage the reverse side of pinion 11.
- In operation the valves 6, 7 as shown in Fig. 1 will be closed and in order to open the valves the handle 23 is turned in a clockwise direction, whereupon the valve 6 is opened through the medium of crank wheel 21, rack 17 and pinion 11, and cold water will be delivered from the faucet through inlet 1, chamber 4 and outlet 3 which may be connected to a swinging spout or to a shower fixture or other desired place of delivery.
- Upon turning the handle 23 in a clockwise direction about one-eighth of a revolution the cold water valve stem 15 will be rotated nearly a half revolution which opens the valve sufficiently, to give approximately full flow of cold water. During the first one-eighth revolution of crank wheel 21 the pivot 36 of rack 18 will move upwardly in Fig. 1 through an arc which will not materially open the hot water valve 7 through its connections to the crank wheel.
- Upon further movement of handle 23 in said direction the cold water valve 6 will not be materially further opened during the next one-eighth revolution of handle 23.

Whereas, the hot water valve 7 will be rapidly opened so as to permit a full flow of hot water, while at the same time the cold water valve is opened so as to permit a full flow of cold water when the handle is moved one-quarter of a revolution in a clockwise direction from the position shown in Fig. 1. Further movement of handle 23 in a clockwise direction will close the cold water valve 10 and continue to open the hot water valve so that a flow of only hot water may be delivered as the hot water valve is fully opened when the handle is turned one-quarter revolution. Subsequent further opening of the 15 hot water valve when closing the cold water valve will not add to the flow of hot water, as it is apparent that only a predetermined quantity can flow through the passage controlled by the valve.

20 From the foregoing it will be apparent that if it is desired to change the relative points and the rapidity at which the valves begin to open and close, it may be accomplished by changing the pitch of the threads 25 on the valve stems, or by changing the pinions secured to the upper end of the valve stems to a smaller or greater diameter.

In this respect one valve may be provided 30 with a greater or lower pitch thread on the valve stem, or with a pinion having a tooth portion of a larger or smaller diameter than the other valve and thereby I may provide a device in which the valves may open and 35 close in varying degrees and at varying times relative to one another.

I claim:

1. The combination with a plurality of 40 faucets each having a screw valve stem; of handle controlled means operatively connected to said screw valve stems and adapted upon operation of said handle in a single direction for opening one of said valves before the other, and then opening the other of said valves and closing the first opened 45 valve; and a single handle for operating said means.

2. In a device of the character set forth, 50 including screw valves; a valve operating mechanism comprising pinions secured on the valve stems of said screw valves; a crank wheel; racks in mesh with said pinions and being connected to said crank wheel; and a handle connected for moving said crank wheel.

55 3. In a device of the character described, including screw valves; a valve operating mechanism comprising pinions secured on the valve stems of said screw valves; a crank wheel; racks in mesh with said pinions and being so connected to said crank wheel that when said crank wheel is rotated a part of a revolution one of said valves 60 will be opened and closed, and the other valve will be opened; and a handle for rotating said crank wheel.

4. In combination, valves having valve stems; a valve operating mechanism comprising pinions secured on said valve stems; racks meshing with said pinions; rack guides on said stems; a crank wheel to which 70 said racks are connected; and a handle for operating said crank wheel.

5. In combination with a double faucet including valves; a valve operating mechanism comprising a base member fitted on 75 said faucet; a cover member secured to said base member; a shaft journalled in said base member and said cover and extending through said cover; and means in said cover actuated by said shaft for opening and 80 closing said valves.

6. In combination with a double faucet including valves having valve stems, a valve operating mechanism comprising a base member 85 fitted on said faucet, a cover member secured to said base member; a shaft journalled in said base member and said cover and extending through said cover; the valve stems extending into said cover, pinions secured on said valve stems; racks in mesh with said pinions; rack guides mounted on said valve stems in said cover for maintaining said racks in mesh with said pinions; a crank wheel secured on said shaft in said cover to which wheel said racks are connected; and a 90 handle on the outer end of said shaft to operate said wheel.

7. An attachment of the character set forth including a base member having openings adapted to receive valve housings, and 100 comprising a plate member; a cover secured to said plate member and forming a housing; pinions adapted to be fixed to valve stems to be operated; and means in said housing to operate said pinions for the purpose set forth.

8. An attachment of the character set forth including a base member adapted to be detachably secured to a faucet; a housing supported by said base member; pinions in 110 said housing adapted to be secured to valve stems to be operated; crank means in said housing; means connected to said crank means and extending in opposite directions and being operably connected to said pinions; and a handle connected to operate said crank means.

9. The combination with a plurality of 120 faucets having valve stems to be operated, valve housings and packing gland nuts screwed onto said housings; of a base member adapted to span the distance between, and be supported on said faucets, by clamping said member between said nuts and said valve housings; a housing carried by said 125 base member and into which housing said valve stems extend; and means in said housing operable by a single handle without said housing to operate one of said valve stems in one direction and then in a reverse direction. 130

to open and close its valve and to operate the other of said valve stems in one direction to open its valve.

10. An attachment of the character set forth comprising a housing; bearings in said housing on diametrically opposite sides thereof; racks in said bearings; pinions in mesh with said racks adapted to be non-rotatably mounted on valve stems to be operated; a handle extending from said hous-

ing; means operably connected to said handle for moving said racks; and a base member extending from said housing adapted to be received on and be secured to the valve housings of valves to be operated.

In testimony whereof, I have hereunto set my hand at Lancaster, California, this 2nd day of October, 1926.

AUSTIN C. WHIDDEN.
